UNITED STATES PATENT OFFICE.

FRANK E. BESSLER, OF AKRON, OHIO.

INNER TUBE.

1,307,769.

Specification of Letters Patent. Patented June 24, 1919.

Application filed September 17, 1918. Serial No. 254,486.

To all whom it may concern:

Be it known that I, FRANK E. BESSLER, a citizen of the United States, residing at Akron, in the county of Summit and State 5 of Ohio, have invented a new and useful Inner Tube, of which the following is a specification.

The device forming the subject matter of this application is a vehicle tire, and the invention aims to provide an inner tube in the 10 form of a helical spring, novel means being provided for controlling the expansion and the contraction of the spring to vary the support which the spring affords for the 15 casing, novel means being provided for reinforcing the spring.

It is within the province of the disclosure to improve generally and to enhance the 20 utility of devices of that type to which the present invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in longitudinal section, a device constructed in accordance with the invention, parts appearing in elevation, and 35 parts being broken away; Fig. 2 is a cross section on the line 2—2 of Fig. 1.

In carrying out the invention, there is provided a felly 1 carrying a rim 2 with which a casing 3 is engaged in any suitable 40 way as shown at 4. A tube 5 is mounted in the felly 1 and is provided at its outer end with a flange 6 abutting against the outer curve of the felly 1 and seated in an opening 7 in the rim 2. A cap 8 is threaded on the inner end of the tube 5 and engages the felly 1, the felly being bound between the cap 8 and the flange 6 on the outer end of the tube.

A winding shaft 9 is mounted for rotation 50 and for longitudinal sliding movement in the tube 5, the outer end of the winding shaft being housed in the cap 8 and being squared or otherwise constructed, as indicated at 10, for the reception of a key. A 55 beveled gear 11 is secured to the shaft 9 intermediate the ends of the shaft and is lo-

cated within the casing 3. A compression spring 12 surrounds a portion of the winding shaft 9, one end of the compression spring abutting against the flange 6 of the 60 tube 5, and the other end of the spring abutting against the beveled gear 11. The outer end of the winding shaft 9 is reduced as shown at 14, to form a shoulder 34. The reduced end 14 of the winding shaft 9 65 passes through the central enlarged part 15 of a support 16 coöperating with the shoulder 34. A securing device 17, such as a nut, is carried by the outer extremity of the reduced end 14 of the shaft 9 and coöperates 70 with the part 15 of the support 16 to hold the reduced end 14 of the shaft 9 in place for rotation. Beveled pinions 18 are journaled on the ends of the support 16 and mesh into the beveled gear 11. The beveled pinions 18 are provided with cylindrical 75 ends 19.

A helical spring, preferably in the form of a metallic ribbon is disposed within the casing 3, the ends 21 of the helical spring 80 being united by means of securing devices 22 with the peripheries of the cylindrical parts 19 of the pinions 18. The terminal convolutions 23 of the spring 20 are inclined toward each other, as shown in Fig. 1 so as to overhang the space which exists between the beveled pinions 18. Owing to this construction, an adequate support for the casing 3 is provided and there is no portion of the casing which is not supported properly by the 90 helical spring 20. Resilient metallic strips 24 extend circumferentially of the structure and are threaded externally of one convolution of the spring 20, and internally of the next convolution, as clearly shown in Fig. 1, 95 the strips 24 being located at the tread of the spring 20 and serving as an important reinforcement therefor. Preferably there are two of the strips 24, these strips being located side by side. As indicated in Fig. 2, 100 one strip passes across the outer surface of each convolution, and the other strip passes across the inner surface of the said convolution of the helical spring. The strips 24 do not engage the convolutions of the helical 105 spring 20 so tightly that these convolutions cannot operate circumferentially with respect to the axis of the spring 20, when the spring 20 is tightened or loosened as herein-after described. The ends 25 of the strips 110 24 are crossed and extended inwardly, within the contour of the helical spring 20, adja-

cent the operating mechanism comprising the shaft 9, the support 16 and attendant parts. If desired, a liner 26, preferably made of canvas, rubber, or other suitable material, may surround the helical spring 20 and engage the casing 3, the inner edges of the liner 26 being spaced to any desired extent, as shown at 27. The liner serves to prevent the casing 3 from being injured or 10 worn by convolutions of the spring 20 or by the metal strips 24.

In practical operation, the supporting effort of the helical spring 20 with respect to the casing 3 may be varied by contracting or 15 expanding the spring. In order to carry out this result, the winding shaft 9 is rotated, the beveled gear 11 rotating the beveled pinions 18 and the latter exerting a twisting effort on the ends of the helical 20 spring 20. The shaft 9 may be prevented from rotating after the spring 20 has been wound, by any suitable means 100.

The spring 12 serves as a support for the shaft 9, the member 15—16 and attendant 25 parts, and permits these elements to move toward and away from the rim 2 when the helical spring 20 is compressed and expanded by the weight imposed thereon.

The strips 24 are made of resilient metal, 30 and serve to strengthen the structure at its tread, the construction being such that these strips do not interfere with the transverse or circumferential movement of the convolutions of the spring 20.

35 Having thus described the invention, what is claimed is:—

1. In a device of the class described, a 40 felly; a rim on the felly and having an opening; a tube in the felly and provided with a flange seated on the felly and located in the opening of the rim; a winding shaft journaled in the tube and slideable longitudinally 45 therein; a beveled gear wheel on the intermediate portion of the winding shaft; a compression spring about the winding shaft and abutting at its ends against the gear 50 wheel and against the flange; a support through which the outer end of the winding shaft is journaled; a securing device on the outer end of the winding shaft and engaging 55 the support to hold the winding shaft therein for rotation; beveled pinions journaled on the ends of the support and meshing into the beveled gear wheel; a helical spring having its ends assembled with the beveled pinions; and a casing connected with

the rim and coöperating with the helical spring.

2. In a device of the class described, a helical spring; a pair or resilient strips located side by side in planes parallel to the axis of the spring, each strip passing externally across the tread portion of one convolution of the helical spring and internally across the tread portion of the next 65 convolution of the helical spring, one strip passing externally across each convolution, and the other strip passing internally across the same convolution, the ends of the strips being located within the contour of the 70 helical spring; means for imparting a twisting effort to the ends of the helical spring; a casing inclosing the helical spring; a rim wherewith the casing is assembled, said means passing through the rim. 75

3. In a device of the class described, a rim; a casing on the rim; a helical spring within the casing; beveled pinions attached to the ends of the spring; a support whereon the pinions are journaled; a winding shaft 80 journaled in the support and passing through the rim; a beveled gear wheel on the winding shaft and meshing into the beveled pinions; and a spring strip extended circumferentially of the rim, the spring 85 strip passing externally across the tread portion of one convolution of the helical spring and passing internally across the tread portion of the next convolution of the helical spring. 90

4. In a device of the class described, a rim; a casing assembled with the rim; a helical spring within the casing and in the form of a ribbon of greater width than thickness; a pair of beveled pinions having 95 cylindrical ends, the ends of the spring extending circumferentially of the cylindrical ends of the pinions; means for securing the ends of the spring to the peripheries of the cylindrical ends of the pinions; a support 100 whereon the pinions are journaled; a winding shaft journaled in the support and extended through the rim; and a gear wheel on the winding shaft, the gear wheel meshing into the pinions. 105

In testimony that I claim the foregoing as my own, I have hereto affixed my signature in the presence of two witnesses.

FRANK E. BESSLER.
